UNITED STATES PATENT OFFICE.

THOMAS F. DIXON, OF PHILADELPHIA, PENNSYLVANIA

METHOD OF PROLONGING THE LIFE OF PRINTERS' RULES.

No. 801,575.

Specification of Letters Patent.

Patented Oct. 10, 1905.

Application filed June 7, 1905. Serial No. 264,068.

To all whom it may concern:

Be it known that I, THOMAS F. DIXON, of Philadelphia, in the State of Pennsylvania, have invented a certain new and useful Method 5 of Prolonging the Life of Printers' Rules, whereof the following is a specification, reference being had to the accompanying drawings as explanatory of the method of procedure.

The ordinary printer's rule consists of a flat 10 strip of brass having a sharpened horizontal edge adapted to make the imprint of a line. The essentials of the structure are that it should have a definite thickness between plane surfaces on each side of proper extent to afford 15 abutments for the faces of the adjacent type and a definite height (or, more properly speaking, width) in order that the printing edge shall lie in the same plane as the faces of the type. Owing to the delicacy of this 20 sharp edge, it is found that the rules deteriorate with great rapidity, since the ordinary handling, and particularly the throwing of the rules into their receptacles, inevitably produces nicks in the edge which mar the 25 regularity of the printed line. The life of a rule may be from six weeks to two months, depending, of course, upon the frequency of its use and the care with which it is handled; but, practically speaking, the rules have to be condemned 30 after a very limited period. As they cost about fifty cents per pound and as they have no value except that of old metal when they are condemned, it is obvious that their perishable character constitutes a very considerable item of expense in a printing-office. 35 It is also obvious that the rules cannot be restored by simply resharpening their printing edges, since this would necessarily reduce their width, and consequently when set up 40 the edge would not be in proper relation to the faces of the type.

The object of my invention is to prolong the life of the rule by such a method of treatment as will permit its edge to be resharpened 45 a number of times, while still preserving the essential characteristics of definite width and definite thickness, so that its normal relations to the type shall not be affected by the renewal of the printing edge.

In the accompanying drawings, Figure I represents a side elevation of an ordinary rule 50 of considerable length; and Fig. II is a similar side elevation, but showing typical instances of nicks in the printing edge. Fig. III is a transverse sectional view of the rule 55 on the line III III of Fig. I. Figs. IV, V, and

VI are transverse sectional views representing different stages in what may be termed the "elementary" method of carrying out my invention; and Figs. VII, VIII, and IX are 60 similar transverse sectional views illustrating the stages in a somewhat more highly organized method of carrying out the invention. Fig. X is a view in side elevation corresponding to the conditions which are indicated in 65 the sectional view of Fig. IX.

In carrying out my method I proceed as follows: When a rule has been nicked to such degree that it is no longer reasonably available for use, I distend its width by lateral 70 pressure applied along and limited to a line or lines running longitudinally with the rule, while at the same time preventing distortion of its general figure. The result of the pressure thus applied is to slightly increase the 75 total width of the rule without changing what may be termed its "practical" dimensions, since the cross-section is only modified at the immediate region to which the pressure is directly applied. The planes of the sides at all 80 other regions than those of immediate application of the pressure, the plane of the bottom, and the planes of the ends remain unchanged in their relation to one another; but by the increase of width the printing edge is 85 uniformly protruded to a sufficient distance to permit of resharpening, which will obliterate the nicks. In thus resharpening the edge it is trimmed so as to restore the normal 90 width of the rule throughout its entire length. 90 It will be seen that the unaffected plane portions of the sides still form abutments for the adjacent type at the same fixed distance apart as before and that consequently the rule, with its protruded and resharpened edge, is for all 95 practical purposes the same as a new rule.

Referring now to the drawings, 1 represents a rule having a printing edge 2, which in Figs. I and III is shown in its normal or unimpaired condition. In Fig. II, I have depicted typical instances of nicking, (indicated at 3.) Fig. IV illustrates the cross-section of the rule 1 after the application of the distending pressure, 4 representing the resharpened edge, and 5 5 being grooves 105 formed at the regions of application of the pressure along lines running longitudinally with the rule.

I prefer to employ a rolling pressure applied simultaneously on both sides of the 110 metal; but as the method itself is not dependent upon the character of the devices which

apply the pressure I do not deem it necessary to describe them in this application. It is only necessary that they should be capable of definitely limiting the region of pressure 5 and that the other regions of the planes of the sides should be maintained against distortion.

When the resharpened rule has again served its purpose and become nicked to an extent 10 which would require condemnation, I repeat the above process, one method of procedure being that indicated in Fig. V, where it will be seen that in addition to the grooves 5 5 a second set of grooves 6 6 has been formed, and 15 for a second resharpening, as shown in Fig. VI, a third set of grooves 7 7 has been formed.

The only limitations of the method are that a sufficient extent of the unaffected plane surfaces at each side of the rule shall be preserved at their initial distance apart to afford proper abutments for the adjacent type.

Instead of proceeding as just stated, where the application of pressure is limited in the first instance to one longitudinal region and 20 is subsequently made along other longitudinal regions, I may proceed in the manner indicated in Figs. VII, VIII, and IX, and in the side view of Fig. X. In this instance the first application of pressure is made along a plurality of longitudinal regions, preferably on 25 both sides of the metal; but the degree of pressure first applied is, relatively speaking, slight, so as to form shallow grooves, as shown in Fig. VII. When resharpening of the edge is required, I repeat the application 30 of the pressure in the same regions, thus deepening the grooves, as indicated in Fig. VII and again as finally indicated in Figs. 35 IX and X. Under some conditions I con-

sider this distribution of the total pressure 40 simultaneously over several regions preferable to its restriction to a single region at a time, since the tendency to distortion of the strip of metal as a whole is somewhat lessened. The principle, however, is obviously the same, 45 and I therefore do not think it necessary to describe it in further detail.

I am of course aware that it is not new to distend metal by the application of pressure, and I do not broadly claim such operation. 50

Having thus described my invention, I claim—

1. The hereinbefore-described method of prolonging the life of a printer's rule, which consists in applying lateral pressure restricted 55 to a limited region running longitudinally with the rule, whereby the edge is protruded; maintaining a substantial extent of the planes of the sides in their normal relation; and resharpening the edge to a line corresponding 60 to the initial printing edge.

2. The hereinbefore-described method of prolonging the life of a printer's rule, which consists in applying lateral pressure restricted to a plurality of limited regions running 65 longitudinally with the rule, whereby the edge is protruded; maintaining a substantial extent of the planes of the sides, in their normal relation, and resharpening the edge to a line corresponding to the initial printing edge. 70

In testimony whereof I have hereunto signed my name, at Philadelphia, Pennsylvania, this 6th day of June, 1905.

Correction in Letters Patent No. 801,575.

It is hereby certified that in Letters Patent No. 801,575, granted October 10, 1905, upon the application of Thomas F. Dixon, of Philadelphia, Pennsylvania, for an improvement in "Method for Prolonging the Life of Printers' Rules," an error appears in the printed specification requiring correction, as follows: In line 38, page 2, the roman letters "VII" should read VIII; and that the said Letters Patent should be read with this correction therein that the same may conform to the record of the case in the Patent Office.

Signed and sealed this 24th day of October, A. D., 1905.

chief Clerk*

apply the pressure I do not deem it necessary to describe them in this application. It is only necessary that they should be capable of definitely limiting the region of pressure 5 and that the other regions of the planes of the sides should be maintained against distortion.

When the resharpened rule has again served its purpose and become nicked to an extent 10 which would require condemnation, I repeat the above process, one method of procedure being that indicated in Fig. V, where it will be seen that in addition to the grooves 5 5 a second set of grooves 6 6 has been formed, and 15 for a second resharpening, as shown in Fig. VI, a third set of grooves 7 7 has been formed.

The only limitations of the method are that a sufficient extent of the unaffected plane surfaces at each side of the rule shall be preserved at their initial distance apart to afford proper abutments for the adjacent type.

Instead of proceeding as just stated, where the application of pressure is limited in the first instance to one longitudinal region and 20 is subsequently made along other longitudinal regions, I may proceed in the manner indicated in Figs. VII, VIII, and IX, and in the side view of Fig. X. In this instance the first application of pressure is made along a plurality of longitudinal regions, preferably on 25 both sides of the metal; but the degree of pressure first applied is, relatively speaking, slight, so as to form shallow grooves, as shown in Fig. VII. When resharpening of the edge is required, I repeat the application 30 of the pressure in the same regions, thus deepening the grooves, as indicated in Fig. VII and again as finally indicated in Figs. 35 IX and X. Under some conditions I con-

sider this distribution of the total pressure 40 simultaneously over several regions preferable to its restriction to a single region at a time, since the tendency to distortion of the strip of metal as a whole is somewhat lessened. The principle, however, is obviously the same, 45 and I therefore do not think it necessary to describe it in further detail.

I am of course aware that it is not new to distend metal by the application of pressure, and I do not broadly claim such operation. 50

Having thus described my invention, I claim—

1. The hereinbefore-described method of prolonging the life of a printer's rule, which consists in applying lateral pressure restricted 55 to a limited region running longitudinally with the rule, whereby the edge is protruded; maintaining a substantial extent of the planes of the sides in their normal relation; and resharpening the edge to a line corresponding 60 to the initial printing edge.

2. The hereinbefore-described method of prolonging the life of a printer's rule, which consists in applying lateral pressure restricted to a plurality of limited regions running 65 longitudinally with the rule, whereby the edge is protruded; maintaining a substantial extent of the planes of the sides, in their normal relation, and resharpening the edge to a line corresponding to the initial printing edge. 70

In testimony whereof I have hereunto signed my name, at Philadelphia, Pennsylvania, this 6th day of June, 1905.
